UNITED STATES PATENT OFFICE.

WILLIAM E. JAMES, OF CARBON, WEST VIRGINIA, ASSIGNOR OF ONE-THIRD TO
EDWARD J. BEER, OF CINCINNATI, OHIO, AND ONE-THIRD TO EMIL F. HOCKE,
OF CARBON, WEST VIRGINIA.

WINDOW-SCREEN.

1,138,295.

Specification of Letters Patent.

Patented May 4, 1915.

Application filed January 30, 1914. Serial No. 815,464.

To all whom it may concern:

Be it known that I, WILLIAM EWART JAMES, a subject of the King of Great Britain, residing at Carbon, in the county of 5 Kanawha, State of West Virginia, have invented certain new and useful Improvements in Window-Screens; and I do hereby declare the following to be a full, clear, and exact description of the invention, such as 10 will enable others skilled in the art to which it appertains to make and use the same.

This invention relates to window screens. The object of the invention resides in the provision of a window screen which embodies a pair of screens mounted at the top and bottom of the window frame respectively upon spring rollers and attached to the upper and lower sashes so that when 15 said sashes are lowered and raised respectively the screens will run out and cover the openings left by the sashes. By this construction the light diffusing qualities of the window are maintained at a greater efficiency than would be the case if the screen 20 occupied a predetermined space in the window frame at all times.

A further object of the invention resides in the provision of a window screen which will not be exposed to the elements when 25 the sashes of the window are in closed position, and which may be easily applied to and removed from a window.

With the above and other objects in view the invention consists in the details of construction and in the arrangement and combination of parts to be hereinafter more 30 fully described and particularly pointed out in the appended claim.

In describing the invention in detail reference will be had to the accompanying drawings wherein like characters of reference denote corresponding parts in the several views, and in which—

Figure 1 is a view in elevation of the 45 inner side of a window showing the sashes raised and lowered respectively, and having the improved screens associated therewith; Fig. 2, a central vertical section of what is shown in Fig. 1; Fig. 3, an enlarged section 50 on the line 3—3 of Fig. 1; Fig. 4, an enlarged section on the line 4—4 of Fig. 2; Fig. 5, a perspective view of one end of one of the screen casings, and Fig. 6, a perspective view of a fragment of one of the screen

casings and showing the manner of swing- 55 ing the casing open to permit access to the screen roller.

Referring to the drawings A indicates a window frame and B and C the upper and lower sashes respectively which are slidably 60 mounted in the frame A in the usual and well known manner. The frame A supports a casing D. This casing D comprises a bottom 11, end members 12 and 13, a top 14, a front member 15, and a rear member 65 16. The top 14, end members 12 and 13 and front and rear members 15 and 16 are formed integral with each other. The front member 15 is hinged to the bottom member 11 as at 17 whereby the bottom member may 70 be swung to afford ready access to the interior of the casing. Pivotal mounted on the end members 12 and 13 are hooks 18 which are adapted to engage respectively with studs 19 carried by the bottom so as to 75 lock the bottom member of the casing against opening movement. Disposed within the casing D at one end thereof is a casing 20 and journaled in the walls of the casing 20 and in the end member 13 is a roller 21, one 80 of the trunnions of said roller extending through the casing 20. Disposed within the casing 20 and encircling said trunnion is a coil spring 22 one end of which is anchored to the trunnion and the other end to the cas- 85 ing 20 whereby rotation of the roller 21 in one direction will energize the spring 22. Having one end secured to and adapted to be wound upon the roller 21 is a screen 23. The casing D is provided with a mouth 24 90 through which the screen 23 is adapted to slide. The free end of the screen 23 has secured thereto a metal strip 26 which is attached to the lower end of the sash C by means of suitable fastening devices 27. The 95 casing D is provided with ears 28 at each end through which fastening devices 29 are passed to positively secure the casing to the window frame. By this construction it will be apparent that as the sash C is raised the 100 screen 23 will follow same and fill the space left open by the sash. This unwinding of the screen from the roller 21 will energize the spring 22 so that upon lowering the sash C the screen will be automatically wound 105 upon said roller.

Secured to the top member of the frame A is a casing E which is similar to the

casing D. Disposed within the casing E is a roller 30 which is similar in every respect to the roller 21. Wound upon the roller 30 is an upper screen 31 one end of which is 5 attached to the upper sash C. Owing to the fact that the upper sash is disposed forward of the lower sash there is mounted on the frame A a guide roller comprising stud bearings 32 secured respectively to the side 10 members of the frame A and rotatable on these bearings 32 is a tubular roller 33 over which the screen 31 is fed.

What is claimed is:—

The combination of a window frame, casings mounted on said frame at the top and bottom thereof respectively, each of said casings including inwardly directed mouths

extending across the entire casing, hinged bottoms included in said casings respectively for affording access to the interior thereof, 20 upper and lower sashes slideable in the frame, spring rollers mounted in said casing respectively, screens wound upon said rollers and trained through the mouths of the containing casing and connected respectively to the 25 upper and lower sashes, and a guide roller mounted on said frame and over which the screen attached to the upper sash travels.

In testimony whereof, I affix my signature, in the presence of two witnesses.

WILLIAM E. JAMES.
